UNITED STATES PATENT OFFICE.

JOHN BRIERLEY, OF PAWTUCKET, RHODE ISLAND, ASSIGNOR OF ONE-FOURTH TO ASA BRIERLEY, OF SAME PLACE.

TANK-RAIL AND ADJUSTABLE BEARING FOR SPINDLES.

SPECIFICATION forming part of Letters Patent No. 242,257, dated May 31, 1881.

Application filed January 10, 1880.

To all whom it may concern:

Be it known that I, JOHN BRIERLEY, of Pawtucket, in the county of Providence and State of Rhode Island, have invented a new and useful Improvement in Tank-Rails and Adjustable Bearings for Spindles, of which the following is a specification.

Figure 1 is a side elevation of the improvement. Fig. 2 is a sectional elevation taken 10 through the line *x x*, Fig. 1, the spindle being in elevation. Fig. 3 is a sectional plan view taken through the line *y y*, Fig. 2.

The object of this invention is to furnish tank-rails and bearings for the spindles of 15 spinning-frames, twisters, and other machines, so constructed that the spindles may be kept lubricated without being liable to heat the oil, that the wear of the spindles can be taken up without moving the spindle or its support, and 20 that the spindles may be centered in the spinning-rings without moving the rings or the ring-rails.

Similar letters of reference indicate corresponding parts.

25 A represents the rail that supports a set of spindles. The rail A is made hollow, and is covered with a plate, B, secured to the upper edges of its sides by screws. The rail A B is designed to receive oil for lubricating the spindles, and should be provided with apertures 30 for pouring in the oil and with stop-cocks or other means for drawing off the oil, which appliances are not shown in the drawings.

35 C is a spindle, the foot of which revolves upon the bottom of the rail A or in a recess in the said bottom. The spindle C passes up through a hole in the top plate or cover, B, of the rail A, and revolves in a tubular bearing or bolster, D, inserted in the said hole. The spindle C is tapered from its foot to its point, and the bolster D is correspondingly tapered on the inside to fit the taper of the spindle. The middle part of the cavity of the bolster D is enlarged, as shown in Fig. 2, to form a chamber 40 to receive the oil that is carried up by the revolving spindle C.

45 Upon the outer surface of the bolster D is cut a screw-thread, to fit into a screw-thread cut in the cavity of the nut or collar E, and to

fit into the screw-thread of the jam-nut F, placed 50 upon it above the said collar E.

The collar E is secured to the top or cover B of the rail A by screws G, as shown in Figs. 1, 2, and 3. The holes in the collar E are made larger than the screws G, so that the said collar can be readily adjusted to center the spindle in the spinning-ring without its being necessary to move the said ring or the ring-rail.

The spindle C is provided with a pulley, H, in the usual way, to receive the driving-band. 60

With this construction the lower part of the spindle C revolves in an oil-tank, so that it will be kept lubricated, and in which the quantity of oil is so great that the oil will not be liable to become heated. With this construction, also, as the spindle C wears the bolster D can be screwed down by loosening the jam-nut F, so as to take up the wear and keep a snug fit. The jam-nut F is then turned down 65 against the collar E to lock the bolster D in 70 place.

The upper end of the bolster D may be countersunk, as shown in Fig. 2, to receive any oil that may work out at the upper end of the said bolster.

75 I am aware that a spindle-rail containing within itself a series of vertical chambers for the reception of the spindle-bolsters, and connected by an oil-duct, is old, and such I do not wish to be understood as claiming, broadly, as 80 of my invention.

Having thus fully described my invention, I claim as new and desire to secure by Letters Patent—

1. The combination, with the spindle C and bolster having an exterior screw-thread, of the hollow rail A, having a bearing formed in the bottom thereof for the lower end of said spindle, a cover, B, for said rail, having an enlarged opening for said bolster and spindle, 85 and the laterally-adjustable collar E, secured to said cover and having an interior screw-thread, in which said bolster is adjustably secured, the several parts arranged relatively to each other substantially as and for the purpose herein shown and described.

2. The combination, with the spindle C and bolster having an exterior screw-thread, of

the hollow rail A, having a bearing for the lower end of said spindle, the cover B for said rail, having an enlarged opening for said bolster and spindle, the laterally-adjustable collar E, secured to said cover and having an interior screw-thread, in which said bolster is adjustably secured, and the jam-nut F, the sev-

eral parts arranged relatively to each other substantially in the manner as and for the purpose herein shown and described.

JOHN BRIERLEY.
